UNITED STATES PATENT OFFICE.

JOSEPH F. JOY, OF PITTSBURGH, PENNSYLVANIA.

GATHERING MECHANISM.

Application filed June 11, 1920, Serial No. 388,156. Renewed November 1, 1922. Serial No. 598,436.

To all whom it may concern:

Be it known that I, JOSEPH F. JOY, a citizen of the United States of America, residing at Pittsburgh, in the county of Allegheny and State of Pennsylvania, have invented certain new and useful Improvements in Gathering Mechanisms, of which the following is a specification.

This invention relates to certain new and useful improvements in gathering mechanisms for coal loading machines, and more particularly for that class of loading machines adapted to transfer coal from the mine floor to conveniently placed cars for transportation from the mine.

Specifically, the present invention contemplates improvement of the general form of gathering mechanism shown, described and claimed in my U. S. Patent #1,806,064, dated June 10, 1919.

The primary object of the invention is to provide an improved gathering arm construction which will be extremely durable and efficient in operation by reason of the particular provision for yieldably or pivotally mounting the finger member of the gathering arm so as to insure movement thereof without obstruction over irregularities of the mine floor and the like.

A further object of the invention is to provide a gathering mechanism including a gathering arm, and means to move the same in a fixed non-circular orbital path, the gathering arm being provided with upwardly extending cutter bits which increase in height gradually rearwardly from the tip of the arm whereby the arm will efficiently penetrate standing shattered coal and pull the same down as well as toward and upon a loading conveyor at each cycle of operation of the gathering arm.

Further objects will become apparent as the nature of the invention is better understood, and the same consists in the novel form, combination and arrangement of parts hereinafter more fully described, shown in the drawings and claimed.

In the drawings, wherein like reference characters indicate corresponding parts throughout the several views,

Figure 1 is a top plan view of a gathering mechanism constructed in accordance with the present invention and carried at the forward end of a loading conveyor,

Figure 2 is an enlarged plan view, partly broken away, of the gathering arm detached, and

Figure 3 is an enlarged view of the gathering arm partly in side elevation and partly in longitudinal section, the finger member of the arm being indicated in upwardly swung position by dotted lines.

Referring more in detail to the several views, the loading machine in connection with which the present gathering mechanism is used, broadly includes a gathering head or apron A carried by the lower forward end of a loading conveyor B of the usual and well known chain and scraper type whose foot shaft 5 is driven in the usual manner by the engagement of the sprocket chains of the endless conveyor member, not shown, with the sprocket wheels 6 carried by said shaft 5.

As is the case with the mechanism of my above mentioned patent, the present gathering mechanism includes a disk 7 upon the head A at each side of the conveyor B, the disks 7 having teeth upon their under faces in mesh with bevel gears 8 upon the opposite ends of the shaft 5, whereby, when continuous rotation is imparted to shaft 5, the disks 7 are caused to continuously rotate in the direction of the arrows a.

Each disk 7 is provided with an upwardly extending stub shaft 9 which extends through an aperture 10 of the hub member 11 of one of the gathering arms. The hub members 11 are suitably retained on the stub shafts 9, so that they may be free to swing horizontally relative to the disks 7, and they have laterally projecting socketed portions 12 in which the inner ends of the squared guide rods 13 are secured. Swiveled on the shoe A for horizontal oscillation are suitable guide members 14 through which the guide rods 13 slidably extend. The hub members 11 are provided with substantially square end sockets 15, the forward portions of the upper walls of which are cut away on an incline as at 16 to provide clearance so as to allow limited upward swinging movement of the gathering arm finger members 17 from the full line to the dotted line position thereof as shown in Fig. 3, the under parts of the inner ends of the finger members 17 being also cut away at an incline as at 18 for permitting this limited

swinging movement of the finger members. The finger members 17 are pivotally connected to the hub members 11 for vertical swinging movement by means of transverse 5 pivot pins or bolts 19 which extend horizontally through apertures provided in the socketed portions of the hub members and in the inner end portions of the finger members, the apertures of the hub members and 10 finger members being horizontally enlarged as at 20 so as to insure freedom of movement for the finger members upon their pivots 19. If the pins 19 are in the form of bolts, nuts 21 are threaded upon the same 15 and locked thereon in any well known manner. The finger members 17 are provided with a plurality of vertical bores or sockets 22 arranged in a longitudinal series as shown clearly in Figs. 2 and 3, and the 20 shanks of suitable cutter teeth 23 are suitably secured in these bores so that said cutter teeth project upwardly from the finger members a greater distance gradually from the 25 points or tips of the finger members toward the hub members.

When the shaft 5 is rotated, rotation is imparted to the disk 7 for causing movement of the gathering arms. The paths described by the tips of the gathering arm fingers are 30 substantially reniform and extend almost entirely beyond the front edge of the shoe A, it being noted that the initial movement imparted to the finger members 17 is longitudinal for easily penetrating a pile of material. The finger members then move laterally and rearwardly to pull down shattered coal and to rake the same onto the conveyor B until they reach a point adjacent the shaft 5, when they recede or move 35 slightly forward and laterally away from the conveyor so as to avoid sweeping the coal off of the conveyor in returning to the start of the penetrating position. The paths are indicated in dotted lines in Fig. 1, and it 40 will be noted that such paths cross each other adjacent the shaft 5 so that it is necessary to move the gathering arms alternately toward and away from the conveyor. 45

From the foregoing description it is believed that the construction and operation 50 of the present invention will be readily understood and the advantages thereof appreciated.

Minor changes may be made without departing from the spirit and scope of the invention as claimed.

What is claimed as new is:

1. In a loading machine, a loading conveyor, a gathering mechanism carried by the 60 lower end of said conveyor including a substantially horizontally arranged gathering arm, means to move the arm in a fixed non-circular substantially horizontal orbital path at the lower end of said conveyor, said arm 65 including an actuated hub member provided

with a socketed portion, and a finger member pivoted in said socketed portion for vertical swinging movement.

2. In a loading machine, a loading conveyor, a gathering mechanism carried by the 70 lower end of said conveyor including a substantially horizontally arranged gathering arm, means to move the arm in a fixed non-circular substantially horizontal orbital path at the lower end of said conveyor, said 75 arm including an actuated hub member provided with a socketed portion, and a finger member pivoted in said socketed portion for vertical swinging movement, said socketed portion of the hub member and the inner 80 end of said gathering finger being similarly cut away to provide clearance for allowing limited swinging movement of the finger member.

3. A gathering mechanism including a 85 horizontally swingable hub member provided with a socketed portion, a horizontal finger member having one end pivoted in the socketed portion of the hub member for vertical swinging movement, said finger 90 member and the socketed portion of the hub member being cooperatively constructed for preventing said finger member from moving below a point wherein the latter is horizontally aligned with said hub member, and 95 means operatively connected to said hub member to move the finger member in a fixed non-circular horizontal orbital path.

4. A gathering mechanism including a horizontally swingable hub member having 100 a socketed portion, a horizontal finger member hingedly mounted in the socketed portion of the hub member for vertical movement, said socketed portion of the hub member and the finger member being operatively 105 constructed for limiting the upward movement of the finger member, and means operatively connected to said hub member to move the finger member in a fixed non-circular substantially horizontal orbital path. 110

5. A gathering mechanism including a horizontally swingable hub member having a socketed portion, a horizontal finger member loosely hingedly mounted in the socketed portion of the hub member for vertical 115 movement, said socketed portion of the hub member and the finger member being cooperatively constructed for limiting the swinging movement of the finger member in opposite directions, and means operatively 120 connected to said hub member to move the finger member in a fixed non-circular substantially horizontal orbital path.

6. A gathering mechanism including a substantially horizontally arranged gathering 125 arm, and means to move said arm substantially horizontally in a fixed non-circular orbital path, said gathering arm including a finger member having cutter bits extending upwardly therefrom at gradually 130

increased heights from the tip of the same inwardly.

5 7. A gathering mechanism including a substantially horizontally arranged gathering arm, and means to move said arm substantially horizontally in a fixed non-circular orbital path, said gathering arm includ-

ing a finger member having cutter bits extending upwardly therefrom at gradually increased heights from the tip of the same 10 inwardly and said finger member being hinged for vertical movement.

In testimony whereof I affix my signature.
JOSEPH F. JOY.
